UNITED STATES PATENT OFFICE.

JOHN NEWBERRY REYNOLDS, OF GREENWICH, CONNECTICUT, ASSIGNOR TO WESTERN ELECTRIC COMPANY, OF NEW YORK, N. Y., A CORPORATION OF ILLINOIS.

MULTIPLE-BRUSH SELECTOR.

1,098,529.

Specification of Letters Patent. Patented June 2, 1914.

Application filed November 16, 1912. Serial No. 731,772.

To all whom it may concern:

Be it known that I, JOHN NEWBERRY REYNOLDS, a citizen of the United States, residing at Greenwich, in the county of Fairfield and State of Connecticut, have invented a certain new and useful Improvement in Multiple-Brush Selectors, of which the following is a full, clear, concise, and exact description.

This invention relates to switching apparatus for use in automatic or semi-automatic exchange systems, and more particularly to those switches in which electro-magnetically controlled switching devices are employed and is adapted for use either as a selector or a connector. By means of this invention a switch is provided by which a large number of lines may be accurately and rapidly served, and whereby any line may be reached through one of a plurality of multiply connected brushes on a common brush shaft, each brush having access to a particular group of lines only. For this purpose there is provided a panel board upon which a plurality of vertical rows of sets of stationary terminals are mounted, each row being divided into sections and each section having a set of co-operative normally inactive movable brushes individual thereto, all the corresponding brushes of each row being connected in multiple. These rows of terminals may be multiplied horizontally across the panel to be accessible to as many individual switching mechanisms as may be necessary to handle the greatest number of simultaneous calls. Each set of brushes is carried by a separate brush carrier mounted on a longitudinally movable brush shaft common to the entire group of brush sets corresponding to a single row of stationary terminals. In accordance with this invention the terminals of any desired line are reached by first causing the set of brushes having access to the section containing the desired line terminals to become active and then causing said set to traverse the terminals in this row until the desired terminals are reached.

One of the objects of this invention resides in the improved means for uniting the corresponding brushes in the several sets in multiple and for extending the telephone circuits to the multiply connected brushes.

Another object resides in the manner of mounting the brushes and in the means for rendering any desired brush active.

Other objects and advantages will appear as the description of the invention progresses.

In the embodiment of my invention, herein shown, all the brush carriers are fixed to the brush shaft to move therewith. To each brush carrier is pivotally secured a set of brushes in such a manner as to be normally rotated to a position to pass over the stationary terminals without engagement therewith. A brush selecting device is provided which is adapted to seize any desired brush set and cause the brushes thereof to assume a position in which they will upon movement of the brush shaft traverse the stationary terminals of their section while the other brush sets remain inactive. This brush selecting means comprises an outwardly projecting trip lever on each brush set, and an auxiliary brush selecting rod parallel to the brush shaft, said rod being provided with a series of inwardly projecting trip fingers, one for each brush set, arranged at progressively increasing distances above the normal position of their respective trip levers. These trip fingers normally extend slightly to one side of the line of travel of the trip levers, means being provided whereby the trip rod may be momentarily rotated to cause the fingers to intercept such line of travel. Thus it will be seen that if during the upward movement of the brush shaft, at the instant the trip lever of any desired brush occupies a position slightly lower than its respective trip finger, the trip rod is momentarily rotated to tripping position, the trip finger of the rod will engage the trip lever of the desired brush set and the brushes will be drawn downwardly into operative position.

For a more detailed description of my invention reference is now made to the accompanying drawings in which—

Figure 1 is a side elevation of one of my switching devices with parts broken away. Fig. 2 is a section on the line 2—2 of Fig. 3. Fig. 3 is a side elevation of a portion of the operating shaft with a part broken away to show the arrangement of the conductors therein, and also showing more clearly the manner of mounting the brush set thereon. Figs. 4 and 5 are a side elevation and a plan view respectively of the brush selecting means in tripping position. Figs. 6 and 7 are a side elevation and a plan view respec-

110

tively of the same after the brush has been tripped. Fig. 8 is a section on the line 8-8, Fig. 1. Fig. 9 is a section on the line 9-9, Fig. 3.

The switch here disclosed is designed to serve 500 lines, the terminals of which are divided into sections of 100 each and are duplicated on the opposite side of the board so as to be accessible to brushes on each side thereof as shown in Fig. 2. It is obvious, however, that the capacity of this switch may be increased by providing a greater number of sections and a correspondingly greater number of brushes, or by arranging more terminals in each section.

In order to avoid needless duplication of the parts and to more clearly illustrate the part of the apparatus claimed as my invention, only one switching device and a portion of one bank of stationary terminals are shown in the drawing. It is to be understood, however, that the stationary terminals are arranged in sets of three each as shown in Fig. 2, and that there are 100 of such sets in each section and five sections to a row. For each section a set of three brushes 1, 2, 3 and 4 are provided, 2 and 3 being in effect one brush, adapted to engage all the sets of stationary terminals 5, 6 and 7 respectively, in its respective section only. Each individual switching apparatus comprises an operating shaft 8, slidably mounted in the guides 9, secured in the frame members 10. Upon the shaft are secured a plurality of brush carriers 11, one for each stationary terminal section. These brush carriers are rigidly secured to the shaft by means of clamping rings 12 and the bolts 13. Each carrier has a pair of outwardly projecting ears 14 and 15 between which are secured the brush set structure 16 by means of the pivot bolt 17. Each brush set comprises, in addition to the brush supporting arms 18, 19, 20 and 21 which are separated from each other and from the clamping plates 28 and 29 by the insulating plates 22 and from the pivot bolt 17 by the insulating sleeve 23, a trip lever 24 having a right angular extension 25. Each of the brush arms has a right angular upward extension 26 ending in the soldering terminals 27. The several parts of the brush set just mentioned are secured together by the screw 31, an insulating sleeve 32 being provided between said screw and the extensions on the brush supporting arms. To hold the brush set in either its operative or inoperative position a spiral spring 33 is provided. This spring is secured at one end to an outwardly extending lug 34 on the side plate 29, and at the other end to an arm 40 on the brush carrier. It is thus so arranged that when the brush set is raised to its inoperative position the axis of the spring will assume a position at one side of the pivot bolt 17, and when the

set is depressed to operative position the spring will lie on the other side of the pivot bolt thus tending to retain the brushes in either position.

Rotatably secured in the frame parallel to the shaft 8 is the brush selecting trip rod 41. Secured between the fixed collars 43 and the pins 44 on the rod are a plurality of sleeves 42, one for each set of brushes. A notch 45 is formed in each sleeve to receive the pin 44 whereby the rotation of the sleeves on the rod is limited. Springs 46 are provided, each having one end secured to a fixed collar 43 and the other end to one of said sleeves respectively in such a manner as to normally tend to rotate the sleeves in a clock-wise direction as viewed from above. Each sleeve 42 has a trip finger 47 extending outwardly therefrom. These fingers are normally in alinement with their ends slightly back of the line of travel of the trip levers 24 as shown in dotted lines in Fig. 5 and in solid lines in Fig. 2, and are arranged at progressively increasing distances above the normal position of their respective trip levers. It will now be seen that if the shaft is moved upwardly until the extension 25 on the trip lever of any desired brush set occupies a position in a plane immediately below its respective trip finger and the trip rod is then rotated the trip finger individual to the selected set will engage the vertical portion of its respective trip lever 24 and will be retained in the line of travel thereof, the rod turning 100 in the sleeve 42. The other trip fingers will not engage their respective trip levers at this time being positioned either above or below the same, respectively, but will pass through the line of travel of the trip levers to the other side thereof as shown in solid lines in Fig. 7. Upon the continued upward movement of the brush shaft the brush set will be depressed to operative position and the trip lever passing from contact with the trip finger as shown in Fig. 6 will allow the trip finger to be rotated to a position in alinement with the other trip fingers by a spring 43. When the brush shaft has passed beyond its brush selecting stage, the trip magnet 54 will be deenergized and the trip rod will be returned to its normal position.

Upon the lower end of the shaft 41 is a disk 48 having at one side thereof an outwardly projecting pin 49. Loosely engaging the pin 49 is the end of a right angular extension 50 on the lever 51. This lever is pivotally mounted at 52 and carries on one side thereof the armature 53 of the electromagnet 54. Thus it will be seen that upon the energization of the electromagnet 54 the rod 41 will be caused to rotate. For the purpose of returning the rod 41 to its normal position a spring 55 is provided hav-

ing one end secured to the side of the disk 48 adjacent the shaft 8, and the other end fixed to an ear 56 carried by the frame member 10.

Upon observing the relation of the trip fingers to their respective trip levers at the moment the rod is rotated, it will be seen that due to the arrangement of the fingers at different distances above the normal position of their coöperating trip levers, only the finger related to the desired brush will be engaged by a trip lever as the other trip fingers immediately pass to the other side of the line of travel of the trip levers. At this time some of the trip levers may lie above and some below their respective trip fingers, or all may lie above or all below depending on which of the several brush sets are selected. The upward movement of the shaft may be continued until the desired terminals are reached.

The shaft is elevated by its being gripped between the drive pulley or drum 57 on the constantly rotating shaft 58 and the idler pulley 59 located on the opposite side of the shaft. The pulley 59 is mounted on the upper end of the lever 60 which is pivotally secured to the frame member 61 and to the lever 62 by the pivot pin 63. The stop pin 64 is provided on the lever 62 to limit the relative movement of the levers. A spring 65 having one end secured to the lever 60 below its pivot point and the other to a downwardly projecting lug 66 on the lever 62 tends to retain the lever 60 in engagement with the stop pin 64. The tension of this spring may be adjusted by the screw-threaded hook 67 secured to one end of the spring and the nut 68.

On one side of the lever 62 adjacent the poles 69 of the clutch magnet 70 is an armature 71 which is normally held in its retracted position by gravity. A screw 72 is provided to adjust the normal distance of the armature from its pole piece. Thus when the magnet 70 is energized it acts through the lever 62, spring 65, lever 60 and idler pulley 59 to force the shaft into engagement with the drive pulley whereby the shaft is elevated to cause the brushes of the selected set to traverse the terminals in its respective selection.

Current for the clutch magnet may be controlled indirectly through the coöperation of the wipers 73 and 74 with the interrupters 75 and 76 and the conducting plate 77. The wiper 73 and the interrupter 75 transmit impulses to the sending mechanism (not shown) by means of which the preliminary movement of the shaft during brush selection may be controlled and the same wiper and the interrupter 76 transmit impulses to measure the travel of the selected brush set over the terminals in the manner clearly disclosed in my co-pending application, Serial No. 637,435 filed July 8, 1941.

While I have shown only one driving means for my shaft, in practice preferably two such driving means of different speeds will be employed as disclosed in my above mentioned co-pending application. When the desired terminal has been reached the upward travel of the shaft will be arrested by the deenergization of the clutch magnet, the shaft being held in its elevated position by the armature release pawl 78 engaging the rack 79 on the shaft 8. This pawl is pivotally mounted in the frame at 80 and is urged toward the rack by the spring 81. When release is desired, the electromagnet 82 is energized, retracting the armature pawl 78 and the shaft is released and may be returned to normal by gravity or in any desired manner. Upon the return to normal of said shaft the actuated brush set is returned to its normal inoperative position by engagement with the shoulder 89 on the guide strip 90. The brush shaft is hollow and the circuit wires 83-84-85 are located therein. Branches from each of these wires are extended to the soldering terminals 27 of corresponding brushes of each set, thus connecting the corresponding brushes of all the sets in multiple. Another branch from each of the conductors 83, 84 and 85 is secured to one of the arms 86 respectively, 95 rigidly but insulatively secured to the brush shaft. These arms each carry a spring finger 87 adapted to slidably engage one of the insulated conducting plates 88 respectively, thus providing means whereby the telephone 100 circuit may be extended to the brushes and the brushes connected in multiple without the use of the pair of wipers individual to each brush as heretofore employed in similar constructions.

What I claim is:

1. In an automatic telephone switch, a brush shaft, a plurality of normally inactive brushes pivotally mounted thereon on axes transverse to the axis of said shaft, a brush selecting device and electromagnetic means for rotating said device to render active a predetermined brush.

2. In an automatic switch, a row of stationary terminals divided into sections, a longitudinally movable brush shaft parallel thereto, a plurality of normally inactive brushes pivotally mounted on said shaft, a brush selecting device, electromagnetic means for rotating said device to render active a predetermined brush and means for determining the time of such rotation.

3. In an automatic switch, a row of stationary terminals divided into sections, an axially movable brush shaft parallel thereto, a plurality of normally inactive brushes pivotally mounted on said shaft on axes at right angles thereto, a brush selecting device, electromagnetic means for rotating said device to render active a predetermined

brush and means for determining the time of such rotation.

4. In an automatic telephone switch, a longitudinally movable brush shaft, a plurality of normally inactive brush sets secured thereto, a trip rod rotatably mounted parallel to said brush shaft and means for rotating said trip rod to render active a predetermined brush set.

10 5. In an automatic telephone switch, a longitudinally movable brush shaft, a plurality of normally inactive brush sets pivotally secured thereto and rotatable in a common plane, a trip rod rotatably mounted parallel to said brush shaft and means for rotating said trip rod to render active a predetermined brush set.

6. In an automatic switching apparatus, a brush shaft, a row of stationary terminals divided into a plurality of sections, a corresponding plurality of normally inactive sets of brushes pivotally mounted on said shaft, a trip rod mounted parallel to said shaft whereby a predetermined brush set 25 may be rendered active and means for moving said shaft longitudinally to cause the selected brush set to traverse the stationary terminals in its respective section.

7. In an automatic telephone switch, a longitudinally movable brush shaft, a plurality of normally inactive brushes pivotally mounted thereon, a trip rod parallel to said shaft, a plurality of trip fingers, one for each brush, on said rod, said fingers being positioned at progressively increasing distances from the normal position of the brushes and in inoperative relation thereto, and means whereby said rod may be momentarily displaced during the longitudinal movement of said shaft to render active a predetermined brush.

8. In an automatic telephone switch, a longitudinally movable brush shaft, a plurality of brush sets pivotally secured thereto, a trip lever rigidly secured to each brush set, a trip rod parallel to said shaft, a plurality of trip fingers on said rod and means for causing one of said trip fingers to operatively engage the trip lever of a predetermined brush set during the preliminary travel thereof.

9. In an automatic switch, a brush shaft, a plurality of normally inactive brushes pivotally mounted thereon, an outwardly projecting trip lever rigidly secured to each brush, a trip rod parallel to said shaft, a trip finger on said rod individual to each

trip lever but normally out of the line of travel thereof, and means for causing a trip finger to intercept the line of travel of the trip lever of a predetermined brush set whereby said set may be rendered active.

10. In an automatic switch, a longitudinally movable shaft, a plurality of normally inactive brush sets pivotally mounted thereon, an outwardly projecting trip lever rigidly secured to each set, a rotatable trip rod parallel to said shaft, a trip finger on said rod for each trip lever, said fingers being positioned at progressively increasing distances from said trip levers and out of the line of travel thereof, and means whereby said rod may be momentarily rotated during the movement of said shaft to effect operative engagement of a trip finger with the trip lever of a predetermined set.

11. In an automatic switch, a longitudinally movable shaft, a plurality of normally inactive brush sets mounted thereon, an outwardly projecting lever on each set, a rotatable trip rod parallel to said shaft, a trip finger on said rod for each trip lever, said fingers being arranged at progressively increasing distances from the normal positions of said trip levers and out of the line of travel thereof, means whereby said rod may be rotated during the travel of said shaft to effect engagement of a trip finger with the trip lever of a predetermined set, means whereby said finger is retained in the line of travel of said lever and means whereby the fingers not thus engaged pass through the line of travel of their trip levers to the other side thereof.

12. In a switch, a plurality of sets of normally inactive movable brushes, a support therefor, a trip lever carried by each of said sets, trip fingers for said trip levers, respectively, normally arranged out of the line of travel thereof, means for simultaneously moving said trip fingers into said line of travel, means for retaining one of said fingers in the line of travel of the trip lever of a predetermined set to trip the same and means whereby the remaining trip fingers pass through the line of travel to the other side thereof.

In witness whereof, I hereunto subscribe my name this 14th day of November A. D., 1912.

JOHN NEWBERRY REYNOLDS.
